UNITED STATES PATENT OFFICE.

ALMON E. NORRIS, OF CAMBRIDGE, MASSACHUSETTS.

BUFFER DEVICE.

1,323,608.

Specification of Letters Patent.

Patented Dec. 2, 1919.

Original application filed September 8, 1911, Serial No. 648,278. Patent No. 1,238,184, dated August 28, 1917. Divided and this application filed May 25, 1917. Serial No. 170,851.

To all whom it may concern:

Be it known that I, ALMON E. NORRIS, a citizen of the United States, and a resident of Cambridge, county of Middlesex, State 5 of Massachusetts, (whose post-office address is 31 Main street, Cambridgeport, Massachusetts) have invented an Improvement in Buffer Devices, of which the following description, in connection with the accompanying 10 drawings, is a specification, like characters on the drawings representing like parts.

This invention relates to buffer devices for moving vehicles, being more particularly though not exclusively intended for the purpose 15 of bringing to rest a movable trolley carriage on an elevated trackway.

This application is a division of my prior copending application Serial No. 648,278, filed September 8, 1911, now patent 1,238,- 20 184, issued Aug. 28, 1917.

The invention will be best understood by reference to the following description when taken in connection with the accompanying illustration of one specific embodiment thereof, while its scope will be more particularly pointed out in the appended claims.

In the drawings:

Figure 1 is an elevation partly broken away showing one end of an elevated trackway equipped with one embodiment of the invention;

Fig. 2 shows the boom at the end of the trackway;

Fig. 3 shows the relation of the boom to an adjacent buffer;

Fig. 4 is a plan of the buffer or bumper mechanism employed in connection with the trolley carriage;

Fig. 5 is a front elevation of the bumper; 40 and

Fig. 6 is a side elevation of the same.

While the invention may have extensive application to other uses, I have herein for the purposes of illustration shown the same 45 applied and particularly adapted to an elevated trackway represented at 1 (Figs. 1 and 2) sustained by a movable bridge structure, represented generally at 2, of the type commonly employed for unloading and conveying coal or other material, as for example, from the vessel indicated at 3 in Fig. 2. In the illustrative embodiment of the invention the trackway 1 sustains the trolley carriage 4, herein of the self-propelled type, mounted to run upon the trolley wheels 5

and sustaining the clam shell bucket 6 controlled by suitable and usual operating ropes, the details of which it is here unnecessary to describe.

I have herein shown an improved device 60 for bringing the trolley to rest at the end of the trackway, such device being capable of bringing the trolley to a full stop under a considerable momentum without excessive shock, while at the same time leaving the 65 trolley released and free for movement in a reverse direction. Referring to the drawings at the terminus of the trackway 1 a buffer frame is provided consisting of side members 7 (Figs. 4 to 6) connected by cross 70 pieces 8. The side members have T rails 9 secured to their lower edges and held substantially parallel with but above the rails 1, the truck wheels being adapted to contact with the broad, depending faces of the T 75 rails when the trolley reaches the buffer. These parts constitute a rigid rectangular frame which is suspended at its two rear corners by the links 10 pivoted at 11 on the fixed uprights 12 attached to the bridge 80 structure 2. The two forward corners of the frame are suspended upon links 13 pivoted at 14 to brackets secured to the fixed cross beam 15. The bolts 16 which connect the members 7 to the links 13 work each in a 85 slot 17 in its link so that the frame is capable of being lifted slightly at its front end relatively to the links 13 as represented in the full line position of Fig. 6. The bolts 16 also serve pivotally to secure to the side 90 members 7 a spring block 18 between which and the corresponding block 19 secured to the bolt 14 there is provided a series of springs 20 of suitable strength to serve the intended purpose.

When the trolley wheel reaches the position represented at *x* in Fig. 6, it contacts with the face of the T rails which latter act as a brake shoe. The momentum of the trolley causes the forward end of the buffer 95 frame to lift slightly and compress the springs 20, this being permitted by a movement of the pins 16 in the slots 17. As the trolley wheel advances beneath the buffer frame, however, the friction of the latter 100 against the wheel increases, the springs 20 exerting an increasing leverage as the wheel moves toward the position *y*. This increased braking effect quickly brings the trolley to rest before the wheel reaches the position *y*. 110

As the trolley moves into the buffer, the buffer frame is prevented from swinging back beyond the rear or full line position by the stops 21. The frame is free, however, to be moved in the opposite direction and any reverse movement thereof tends to swing the frame toward the forward position shown in dotted lines, thereby lifting the frame and immediately relieving the pressure against the wheels.

In Fig. 1 a buffer of the type described is indicated at the inward end of the bridge or trackway. A bridge of this type is ordinarily constructed to overhang the material intended to be conveyed. Where it is utilized for unloading coal from boats, it is ordinarily equipped with a boom overhanging the water. Such boom can be raised out of the way, but when lowered serves to form a continuation of the trackway so that the trolley can be brought directly over the hold of the vessel from which the coal is to be taken.

In Figs. 2 and 3 I have shown the opposite or outer end of the bridge having the boom 22 adapted to be raised or lowered as indicated, the outer or extreme end of the boom being also equipped with the buffer of the type described, so that the trolley can be brought to the extreme end of the boom without danger.

In order to prevent the accidental overtravel of the trolley when the boom is raised, I also preferably employ a buffer at the end 35 of the fixed trackway on the inside of the boom so that when the boom is lifted such buffer will prevent the travel of the trolley beyond that point. As the buffer should not interfere with the travel of the trolley when 40 the boom is lowered, I have also provided means whereby the buffer is automatically moved out of the way of the trolley by the act of lowering the boom.

Referring particularly to Fig. 3, the links 45 23 which support the outer end of the buffer are prolonged and provided with a pin 24 which works in a slot 25 in the end of the link 26. The latter is secured to a bracket 27 on the end of the boom 22 so that when 50 the boom is lowered the link 26 engages the pin 24 at the end of the slot and swings the buffer frame up to the dotted line position indicated where it is entirely clear of the trolley carriage wheels and the trolley carriage. On the other hand, when the boom 55 is lifted, as shown in the full line position in Fig. 3, the buffer frame is dropped to its normal or effective position, the pin 24 having sufficient play in the slot 25 to allow the necessary swinging movement of the frame.

While I have herein shown and described for purposes of illustration one embodiment of my invention, it is to be understood that the same as to many of its features is applicable to hoisting and conveying apparatus

of widely different description from that herein illustrated, and to uses other than in connection with trolley carriages for hoisting and conveying systems. It is also to be understood that extensive deviations may 70 be made from the details of construction and from the relative arrangement of parts without departing from the spirit of this invention.

Claims:

1. In a hoisting and conveying apparatus, the combination with an elevated trackway, of a trolley and a trolley buffer, the latter comprising a buffer frame adapted to engage and check the movement of the trolley 80 wheels, links suspending said frame, means forcing the trolley receiving end of said frame toward the trolley wheels, the suspension of the frame being such as to relieve the pressure on reverse movement of the 85 trolley.
2. The combination with a trackway of a buffer frame, suspension links for said frame, the latter being movable vertically in the suspension links at the trolley receiving end of the frame and resilient means normally pressing said forward end toward a wheel engaging position.
3. The combination with a trackway of a buffer frame, means suspending the same 95 over the trackway providing a compound longitudinal and depression movement on engagement therewith by a wheeled truck, and means yieldingly pressing the truck receiving end of the frame in the suspension 100 means toward the trackway.
4. The combination of a trackway of a buffer member suspended above the trackway, said member being yieldably pressed toward the trackway at its truck receiving 105 end and the buffer support providing for a longitudinal and vertical movement thereof when engaged by a truck.
5. The combination with an elevated trackway, of a trolley and a trolley buffer, 110 the latter being adapted to engage and check the movement of the trolley wheels but yieldable to relieve the checking pressure on reverse movement of the trolley.
6. The combination with a bridge having a 115 boom and a trackway, of a trolley carriage, a buffer at the outer end of the fixed trackway, and means dependent on the movement of the boom for rendering said buffer ineffective.
7. The combination with a bridge having a 120 boom and a trackway, of a trolley carriage, a buffer at the outer end of the fixed trackway, and means dependent on the movement of the boom for rendering said buffer effective.

In testimony whereof, I have signed my name to this specification.

ALMON E. NORRIS.
